US00D959717S

(12) **United States Design Patent** (10) **Patent No.:** **US D959,717 S**
Hsu (45) **Date of Patent:** **** Aug. 2, 2022**

(54) **LAMP**

(71) Applicant: **Dong Guan Jia Sheng Lighting Technology Co., Ltd. China, Guang-Dong (CN)**

(72) Inventor: **Kevin Hsu, Taichung (TW)**

(73) Assignee: **Dong Guan Jia Sheng Lighting Technology Co., Ltd. China, Guang-Dong (CN)**

(**) Term: **15 Years**

(21) Appl. No.: **29/709,626**

(22) Filed: **Oct. 16, 2019**

(51) LOC (13) Cl. **26-02**

(52) U.S. Cl.

USPC **D26/40**

(58) **Field of Classification Search**

USPC D26/37-44, 46-52, 72, 76, 78, 79, 80, D26/81, 82, 83, 85, 86, 88, 90, 113, 118, D26/119, 120, 121, 122, 138, 139, 140,

D26/141, 142; D10/111-115

CPC .. F21V 17/00; G03H 2227/06; G02B 5/1842; Y10S 362/806

(57) **CLAIM**

The ornamental design for a lamp, as shown and described.

DESCRIPTION

FIG. 1 is a perspective view of a lamp showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines shown in the drawings illustrate portions of the lamp and form no part of the claimed design.

1 Claim, 7 Drawing Sheets
